(57) **CLAIM**

The ornamental design for a holder for tubular hairstyling accessories, as shown and described.

DESCRIPTION

FIG. 1 is a perspective view of a holder for tubular hairstyling accessories showing my new design;

FIG. 2 is a top plan view of the holder for tubular hairstyling accessories of FIG. 1;

FIG. 3 is a front elevational view of the holder for tubular hairstyling accessories of FIG. 1;

FIG. 4 is a side elevational view of the holder for tubular hairstyling accessories of FIG. 1, the opposite side being substantially a mirror image of the sides shown;

FIG. 5 is a rear elevational view of the holder for tubular hairstyling accessories of FIG. 1; and,

FIG. 6 is a bottom plan view thereof.
